UNITED STATES PATENT OFFICE.

JACOB E. NEAHR, OF HARTSDALE, NEW YORK.

MATCH SAFE.

Application filed July 6, 1923. Serial No. 649,905.

This invention relates to a smoker's article in the form of a covered ash-receiver. The cover is removable, and provided with a match-safe pendent within the ash-receiver, and also has means to hold ignition slips.

The cover may be made in two portions, comprising an annular or other open frame to fit within the top of the ash-receiver, said frame having a projecting flange to rest 10 upon the brim of the ash-receiver, and also comprising a lid portion which forms the major portion of the cover, and is connected by a hinge to the open frame at or near the top of the match-safe; the ignition slips 15 being locked against displacement when the lid is down. The lid is preferably provided with two pockets for ignition slips, and with an intermediate opening through which ashes and burned matches may be 20 dropped into the ash-receiver.

The match-safe is divided into two compartments by means of a partition, and the latter is extended upwardly above the match-safe to form a support for a cigar 25 rest. Preferably the cigar rest is depressible, and means extends therefrom to the lid to swing the same up when the cigar rest is depressed, whereby the lid may be raised sufficiently to permit it to be caught by the 30 finger, whereby it may be lifted to a vertical position. In the preferred form of the connection the depression of the cigar rest raises the lid about to vertical position.

Other features and advantages will hereinafter appear.

In the accompanying drawings,—

Figure 1 is a plan of an ash-receiver provided with certain of the present improvements.

Figure 2 is a sectional elevation of the same.

Figure 3 is a side elevation of the open frame, with a match-box pendent therefrom, and a cigar rest mounted upon a partition which divides the match-box into compartments.

Figure 4 is a sectional elevation on the line 4—4 of Figure 1, to illustrate the ignition-strip pocket in the lid which covers the 50 ash-receiver.

Figure 5 shows the removable partition seen at Figures 1 to 3, this partition being removable independently of the cover and being surmounted by the cigar rest.

Figure 6 is a sectional view taken through the match-box and the open frame which

supports it; showing the removable partition in place and some of the matches.

Figure 7 is a plan of certain of the improvements in another form, and illustrating two ignition-slip pockets on the hinged lid, and also showing the depressible cigar rest which tilts up the lid preparatory to lifting the same to a vertical position.

Figure 8 is a sectional elevation of the device seen at Figure 7, and illustrates the operation of depressing the cigar rest so as to tilt up the latter.

Figure 9 shows the preferred form of the depressible cigar rest seen at Figure 8. In Figure 9 the cigar rest is connected to lift the lid about to a vertical position, as shown in dotted lines.

Figure 10 shows the sheet-metal blank from which there may be folded the cigar rest and the lever whereby it raises the lid.

An ash-receiver, in the form of a vase or box 10, has a lid or cover 11, and a match-safe 12 depends from said cover into the ash-receiver; the cover having a pocket or provision 13 for holding a match-striking slip 14.

A rim or top frame 15, of annular or other suitable contour, may overhang and rest upon the brim 16 of the ash-receiver 10, which may be an ornamental vase of metal, glass, ceramic ware, wood, etc.; and from this rim 15 depends the match-safe 12, which may extend downwardly towards the bottom of the ash-receiver at the back 90 thereof.

A segmental lid 17 is fitted within the annular top frame 15, and is hinged at 18 to the top of the straight front wall 19 of the match-box, so that when said lid is 95 lifted the ash-receptacle may be dumped. Moreover the interior of the ash-receptacle is rendered accessible without lifting off the annular frame 15. In this lid is formed an opening 20 through which may be dropped 100 burned matches and refuse, said opening preferably extending across the lid close to the match-safe, and the forward edge 21 of said opening serving as a finger hold for raising the lid. The edges may be convexly 105 rounded as shown, for appearance and for convenience of manipulation, the opening being wide enough to admit the finger for raising the lid.

In front of said opening 20 is provided 110 the pocket 13 to hold the match-striking slip or slips, which may consist of the cost.

ed sides 14 of an ordinary safety-match box, the pocket being of sufficient capacity to hold both the coated sides of the match-box, which may be torn therefrom and placed 5 in the pocket at the time that the match-box is emptied into the match-safe 12. This pocket is on the under side of the hinged lid 17, and when the lid is down the match-striking slips cannot be displaced, because 10 they are locked in position by the flange or side wall 22 of the annular rim or frame to which the lid is hinged. By raising the lid, the slips are rendered accessible for withdrawal and replacement.

15 There is also provided upon the annular frame 15 a platform or support 23, in such position that a burning cigar or cigarette placed thereon may be pinched between the support and the lid 17 as the latter descends, 20 thereby extinguishing the cigar. This support 23 affords a convenience upon which to knock a pipe, or by which to knock off the ashes from a cigar.

The match-safe is divided by a removable 25 vertical partition 24 into two compartments, to keep the matches in upright position. This partition may be removable, and may slide up and down in front and rear grooves between vertical raised beads 25 formed in 30 the front and rear walls of the match-safe by bending the metal thereof.

From said partition 24 may rise an extension 26, upon which may be fixed a cigar rest 27, thus making a compact, attractive 35 and saleable combined ash-receiver, match-safe, match-striker, cigar-extinguisher and cigar rest. The cigar rest may extend forward horizontally, and may overhang the hinge portion of the swinging lid 17; and 40 the opening 20 in the top of the latter may be of ample dimensions, so that, when the lid is swung up, the narrowed end of the cigar rest may occupy said opening. This permits ample swing of the lid.

45 Referring now to Figures 7 and 8, the hinged lid 28 is also provided with two ignition-slip pockets 29, 30, flanking a central opening 31 in the lid, this opening also being provided with broad convexly-curved 50 edges 32, for convenience in dropping débris therethrough, and for knocking a cigar end against it to shake off the ashes. The slips 14 in both pockets are locked by the brim portion of the open frame 22 against end- 55 wise displacement when the lid is down. The support 33 on the open frame beneath the lid is inclined downwardly and forwardly to co-operate with an inclined projection 34 under the lid, for extinguishing a cigar. 60 This support is convenient to knock a pipe against, and for other purposes, as the ashes readily fall off therefrom into the receiver. The projection 34 under the lid may be in 65 the form of a tongue which is bent downwardly to an inclined position, the sides of

the projection being folded upwardly at 35 to form supports connecting the inclined projection 34 to the lid. When the inclined projection becomes heated, the heat will not readily spread to the top of the lid. 79

The cigar rest 36 is depressible, being mounted upon an arm 37 which is pivoted at 38 to the upper end of the partition 39 in the match-box. An arm 40 extends forwardly from the pivot, said arm 40 being 75 raised when the cigar rest is depressed, and pressing up against the under side of the lid to tilt the same up about its pivot far enough so that it may be readily caught by the finger and raised to a vertical position. The 80 cigar rest 36 thus serves the function of a finger-piece for raising the lid. The parts 37-40 may consist of two plates bestriding the top of the partition 39, and fitted closely to the same, so as to hold the cigar rest 85 against lateral displacement. These two plates may be formed integral with the cigar rest, and may be folded down from the edges of the cigar rest and close to the under side of the same, as at 41; the parts 36-40 being 90 preferably a single piece of metal.

Variations may be resorted to within the scope of the invention, and portions of the improvements may be used without others.

Having thus described my invention, I 95 claim:—

1. The combination with an ash-receiver, of an open removable top frame for said ash-receiver, a match-safe depending from said frame within the ash-receiver, and a lid hinged to the upper part of the match-safe and conforming with said frame, said lid provided with a pocket for a match-striking slip, and also having an opening through which to drop burned matches. 105

2. The combination with an ash-receiver, of an open removable top frame for said ash-receiver, a match-safe depending from said frame within the ash-receiver, and a lid hinged to the upper part of the match-safe 110 and conforming with said frame, said lid provided with a pocket for a match-striking slip and also having an opening through which to drop burned matches, said opening serving as a finger-hold for raising the lid, and the edges of the opening being convexly rounded, the opening being wide enough to admit the finger for raising the lid. 115

3. The combination with an ash-receiver, of an open removable top frame for said ash-receiver, a match-safe depending from said frame within the ash-receiver, and a lid hinged to the upper part of the match-safe and conforming with said frame, said lid provided with a pocket for a match-striking slip, and also having an opening through which to drop burned matches, said pocket being of proportions to fit the ignition sides obtained from an ordinary safety-match box, and the open removable frame 120

serving to lock the slips in the pocket when the lid is down, said pocket being on the underside of the lid.

4. The combination with an ash-receiver, of an open removable top frame for said ash-receiver, a match-safe depending from said frame within the ash-receiver, and a lid hinged to the upper part of the match-safe and conforming with said frame, said lid provided with a pocket for a match-striking slip, and also having an opening through which to drop burned matches, a support being provided upon said open frame to co-operate with the lid to pinch and extinguish a cigar.

5. The combination with an ash-receiver, of an open removable top frame for said ash-receiver, a match-safe depending from said frame within the ash-receiver, a lid hinged to the upper part of the match-safe and conforming with said frame, a vertical partition dividing the match-safe into compartments, and said partition provided with an upward extension, and a cigar rest 25 mounted upon said upward extension above the matches.

6. The combination with an ash-receiver, of an open removable top frame for said ash-receiver, a match-safe depending from said frame within the ash-receiver, a lid hinged to the upper part of the match-safe and conforming with said frame, and depressible means mounted upon said frame for lifting said lid.

35 7. The combination with an ash-receiver, of an open removable top frame for said ash-receiver, a match-safe depending from said frame within the ash-receiver, a lid hinged to the upper part of the match-safe and conforming with said frame, a vertical partition dividing the match-safe into compartments, and said partition provided with an upward extension, a cigar rest mounted upon said upward extension above the matches, said cigar rest being mounted for movement, and means to enable it when depressed to raise said lid about to vertical position.

8. The combination with an ash-receiver, 50 of an open removable top frame for said ash-receiver, a match-safe depending from said frame within the ash-receiver, a lid hinged to the upper part of the match-safe and conforming with said frame, a vertical partition dividing the match-safe into compartments, and said partition provided with an upward extension, and a cigar rest mounted upon said upward extension above the matches, said cigar rest having an arm which is pivoted to the partition in said match-safe, and having means to lift said lid.

9. The combination with an ash-receiver, 55 of an open removable top frame for said ash-receiver, a match-safe depending from said frame within the ash-receiver, a lid hinged

to the upper part of the match-safe and conforming with said frame, a vertical partition dividing the match-safe into compartments, and said partition provided with an upward extension, a cigar rest mounted upon said upward extension above the matches, said cigar rest being mounted for movement, and means to enable it when depressed to raise said lid, the lid being liftable independently of said cigar rest.

70 10. The combination of an ash-receptacle provided with a lid, a cigar rest supported upon said receptacle, and a connection from the cigar rest to the lid to enable depression of the cigar rest to raise the lid.

80 11. The combination of an ash-receptacle provided with a lid, a cigar rest supported upon said receptacle, and a connection from the cigar rest to the lid to enable depression of the cigar rest to raise the lid, the lid being 85 also liftable independently of the cigar rest.

12. The combination with an ash-receiver, of an open removable top frame for said ash-receiver, a match-safe depending from said frame within the ash-receiver, a lid 90 hinged to the upper part of the match-safe and conforming with said frame, a vertical partition dividing the match-safe into compartments, and said partition provided with an upward extension, and a cigar rest 95 mounted upon said upward extension above the matches, said cigar rest having an arm which is pivoted to the partition in said match-safe, and having means to lift said lid, said arm consisting of two plates bestriding the partition to hold the cigar rest against lateral displacement.

100 13. The combination with an ash-receiver, of an open removable top frame for said ash-receiver, a match-safe depending from said frame within the ash-receiver, a lid hinged to the upper part of the match-safe and conforming with said frame, a vertical partition dividing the match-safe into compartments, and said partition provided with an 110 upward extension, and a cigar rest mounted upon said upward extension above the matches, said lid provided with two pockets for ignition slips, and with an opening between said pockets in such position that slips 115 placed in the pockets are locked against displacement when the lid is down.

14. The combination with an ash-receiver, of an open removable top frame for said ash-receiver, a match-safe depending from 120 said frame within the ash-receiver, and a lid hinged to the upper part of the match-safe and conforming with said frame, said lid provided with a pocket for a match-striking slip, and also having an opening through which to drop burned matches, a support being provided upon said open frame to co-operate with the lid to pinch and extinguish a cigar, said support being inclined downwardly, and said lid having a downwardly- 125 130

inclined projection to co-operate therewith to extinguish a cigar.

15. The combination with an ash-receiver, of an open removable top frame for said ash-receiver, a match-safe depending from said frame within the ash-receiver, and a lid hinged to the upper part of the match-safe and conforming with said frame, said lid provided with a pocket for a match-striking slip, and also having an opening through which to drop burned matches, a support

being provided upon said open frame to co-operate with the lid to pinch and extinguish a cigar, said support being inclined downwardly, and said lid having a downwardly-inclined projection to co-operate therewith to extinguish a cigar, the projection being upon the under side of the lid, and in the form of a tongue bent downwardly thereunder.

15

JACOB E. NEAHR.
